UNITED STATES PATENT OFFICE.

GEORGE J. B. RODWELL, OF BUFFALO, NEW YORK, ASSIGNOR TO RODWELL SIGN COMPANY,
OF BUFFALO, NEW YORK, A CORPORATION OF NEW YORK.

SIGN.

No. 896,328.

Specification of Letters Patent.

Patented Aug. 18, 1908.

Application filed November 2, 1904. Serial No. 231,071.

To all whom it may concern:

Be it known that I, GEORGE J. B. RODWELL, residing at Buffalo, in the county of Erie and State of New York, have invented 5 certain new and useful Improvements in Signs, of which the following is a full, clear, and exact description, such as will enable others skilled in the art to which it appertains to make and use the same.

10 This invention relates to signs, display cards and articles of a like nature.

A general object is to provide a simple and inexpensive device of the above type which shall attract and hold the attention of a by- 15 passer.

Another object is to provide a durable device of the above type in which letters or other designs of any desired configuration may be formed in such manner as to have a 20 brilliant reflecting surface and artistic appearance.

Another object is to provide a device of the above type in which the brilliantly reflecting letters shall appear against a relatively dark or dull background. 25

Other objects will be in part obvious and in part pointed out hereinafter.

The invention accordingly consists in the features of construction, combinations of 30 elements and arrangement of parts which will be exemplified in the device herein described and the scope of the application of which will be indicated in the following claims.

35 In the accompanying drawings, wherein is shown one of various possible embodiments of my invention, Figure 1 is an elevation of the same. Fig. 2 is a cross section taken on the line $x-x$ of Fig. 1. Fig. 3 is an enlarged 40 detail section taken upon the above line.

Similar reference characters refer to similar parts throughout the several views.

Preliminary to a description of my invention, it may be noted that in devices of the 45 nature of those with which this invention deals, it is necessary that the lettering or other design be prominent and stand out as clearly as possible from the surrounding surface. This is best accomplished by making 50 this part appear luminous, either by means of light from an independent source transmitted through the same or by means of reflecting the light cast upon the outer surface thereof. Obviously, the latter is the simpler 55 and more economical course, but it necessi-

tates the protection of the reflecting surface in order to prevent any natural accumulation thereon. It is also highly desirable that this reflecting surface be provided with depressions whereby an irregular reflection is attained and an artistic effect produced which readily attracts attention. In order best to attain the above results it is requisite to use a soft metal reflecting member, as, for example, tin, as a hard surface will not take a share 60 impression from the die by which it is shaped. If metal of this nature is used, it is necessary to protect the same from distortion under varying conditions of use. The above and other advantages are attained in constructions of the nature of that herein described. 70

Referring now to Fig. 1 of the drawings, there is represented at 1 a plate, preferably of glass or similar material, the rear surface of which is painted as at 2 or the plate is otherwise rendered opaque except in certain portions having the configuration of the design which it is desired to form. Beneath these translucent parts 3 is a thin metallic sheet 4 of soft metal, preferably solid tin, which as 80 here shown extends substantially over the entire rear surface of the plate 1. This sheet 4 is stamped or otherwise formed, preferably by a die, so as to have over the outer surface beneath the translucent parts 3 85 a series of similar depressions 5. The artistic effect is enhanced if certain larger depressions 6 are provided of a "jewel" form, that is, having a number of symmetrically arranged facets similar to those formed upon the outer convex surface, of some cut stones. Over these large depressions or "jewels", upon the rear surface of the glass is a thin film of translucent coloring matter 7 which corresponds in outline with the depression 90 over which it is placed and thus gives the effect of a colored stone. 95

Although the soft metal which provides the reflecting surface is well adapted to receive a sharp impression from the die and 100 otherwise to perform the functions which it is intended to accomplish, nevertheless it is highly desirable to provide some protective cover for the same in order to prevent bending, tearing or other distortion or mutilation 105 thereof. This is preferably accomplished by means of a thin plate 8 of harder metal, as, for example, brass. This plate is stamped by the same die with which the sheet 4 is 110 formed and thus receives a surface corre-

sponding exactly to the surface of sheet 4. Sheets 4 and 8 are then placed so as to cause the depressions therein exactly to register, and, the plate 1 being placed in position over sheet 4, the outwardly projecting edges 9 of the sheet or backing 8 are turned over the beveled edges of said plate. If desired, a chain 10 may be connected to the backing 8 by means of eyes 11 and the sign is thus adapted to be suspended in any desired position.

By the word "soft" as used throughout this description and in the following claims it is intended to describe a substance having about the same degree of malleability and ductility as substantially pure tin. The expression, however, is used in a broad sense and is intended to comprehend a considerable range of these qualities, the idea which it is intended to bring forth being that the substance which is described thereby is well adapted to receive a sharp impression from a die and is nevertheless somewhat liable to distortion or mutilation if unprotected. The word "hard" as used herein and throughout the claims is used in a relative sense.

The method of use of the invention herein described will be obvious, but it may be noted that the application of the same is extremely broad and in no wise limited to the form of portable sign or display card herein described.

It will thus be seen that I have provided a durable, simple and inexpensive sign or display card and that the same is well adapted to attract and hold attention. The appearance of the same is artistic and the construction is simple, the several parts being largely formed by means of unskilled labor.

As many changes could be made in the above construction and many apparently widely different embodiments of my invention could be made without departing from the scope thereof, I intend that all matter contained in the above description and shown in the accompanying drawings shall be interpreted as illustrative and not in a limiting sense.

Having described my invention, what I claim as new and desire to secure by Letters Patent is:

1. In a device of the class described, in combination, a member having translucent portions of a predetermined configuration, a soft metallic member resting against said first-mentioned member opposite the translucent portions thereof, said metallic member being provided with a plurality of depressions upon the surface thereof exposed through said translucent portions of said first-mentioned member, and coloring matter interposed between said translucent member and the depressions in said soft metallic member.

2. In a device of the class described, in

combination, a member having a translucent portion of a predetermined configuration, a soft metallic member resting against said first-mentioned member opposite the translucent portion thereof, said second mentioned member being provided with depressions, coloring matter interposed between said translucent portion and a portion of the depressions in said soft metallic member, and a protective covering over said depressions. 70 75

3. In a device of the class described, in combination, a member having certain portions thereof translucent and of a predetermined configuration, a soft metallic plate resting against said member and having depressions in the exposed surface thereof, and a second member having similar depressions registering with said first-mentioned depressions and adapted to protect the same from distortion. 80 85

4. In a device of the class described, in combination, a member having translucent portions of a predetermined configuration, a relatively soft metallic member resting against said first-mentioned member and having depressions therein opposite said translucent portions, coloring matter interposed between said first-mentioned member and said depressions, and a relatively hard metallic member having similar depressions registering with said first-mentioned depressions and adapted to protect the same from distortion. 90

5. In a device of the class described, in combination, a member having translucent portions of a predetermined configuration, a relatively soft metallic member resting against said first-mentioned member and having depressions therein opposite said translucent portions, coloring matter interposed between said first-mentioned member and said depressions, and a relatively hard metallic member having similar depressions registering with said first-mentioned depressions and adapted to protect the same from distortion, the edges of said last-mentioned member projecting beyond and being bent over said first-mentioned member. 100 105 110

6. In a device of the class described, in combination, a member provided with translucent portions of a predetermined configuration, a soft metallic member resting against said first-mentioned member and provided with depressions at points opposite said translucent portions, and a member provided with similar depressions registering with and fitting the rear surface of said first-mentioned member, the edges of said last-mentioned member projecting beyond and being bent over the edges of said first-mentioned member. 115 120 125

7. In a device of the class described, in combination, a member having certain portions thereof translucent of a predetermined configuration, a relatively soft metallic plate 130

resting against said member and having depressions in the exposed surface thereof, and a second relatively hard member having similar depressions registering with said first-mentioned depressions and adapted to protect the same from distortion.

8. In a device of the class described, in combination, a translucent member having a portion of the surface of one of its sides covered with a relatively opaque substance, the uncovered portion being of a predetermined configuration, a soft metallic member resting against said first-mentioned member opposite the uncovered portion thereof, and coloring matter interposed between the uncovered portion of said translucent member and said soft metallic member.

9. In a device of the class described, in combination, a member having translucent portions of a predetermined configuration, a second member resting against said first-mentioned member having a plurality of depressions each constituted by a series of symmetrically arranged reflecting facets arranged opposite said translucent portions, and translucent coloring matter interposed between said translucent portions and said depressions.

10. In a device of the class described, in combination, a member having translucent portions of a predetermined configuration, a soft metallic member resting against said first-mentioned member having a series of depressions, each depression constituted by a plurality of symmetrically arranged reflecting facets, said depressions being arranged opposite the translucent portions of said first-mentioned member, and translucent coloring matter interposed between the translucent portions of said first-mentioned member and the depressions of said second-mentioned member.

11. In a device of the class described, in combination, a member having a translucent portion of a predetermined configuration, a soft metallic member resting against said first-mentioned member having a series of minute depressions, and a series of larger depressions, said larger depressions being constituted by a series of symmetrically arranged facets adapted to form a brilliant reflecting surface, all of said depressions being arranged opposite said translucent portions.

12. In a device of the class described, in

combination, a member having a translucent portion of a predetermined configuration, a soft metallic member resting against said first-mentioned member having a series of minute depressions and a series of larger depressions, said larger depressions being constituted by a series of symmetrically arranged facets adapted to form a brilliant reflecting surface, all of said depressions being arranged opposite said translucent portions, and translucent coloring matter interposed between the translucent portion of said first-mentioned member and the larger depressions of said soft metallic member.

13. In a device of the class described, in combination, a member having translucent portions of a predetermined configuration, a relatively soft metallic member resting against said first-mentioned member having a series of minute depressions, a plurality of larger depressions, said larger depressions being constituted by a series of symmetrically arranged facets adapted to form a brilliant reflecting surface, all of said depressions being arranged opposite said translucent portions, and a second relatively hard metallic member having similar depressions registering with said first-mentioned depressions and adapted to protect the same from distortion.

14. In a device of the class described, in combination, a member having a translucent portion of a predetermined configuration, a relatively soft metallic member resting against said first-mentioned member having a series of minute depressions, and a series of larger depressions, said larger depressions being constituted by a series of symmetrically arranged facets adapted to form a brilliant reflecting surface, all of said depressions being arranged opposite said translucent portions, translucent coloring matter interposed between the translucent portions of said first-mentioned member and the larger depressions of said relatively soft metallic member, and a second relatively hard metallic member having similar depressions registering with said first-mentioned depressions and adapted to protect the same from distortion.

In testimony whereof I affix my signature, in the presence of two witnesses.

GEORGE J. B. RODWELL.
